SAXOPHONE

Filed Oct. 22, 1924

2 Sheets-Sheet 2

UNITED STATES PATENT OFFICE.

AVERY J. HILTON, OF GLOUCESTER, MASSACHUSETTS.

SAXOPHONE.

Application filed October 22, 1924. Serial No. 745,201.

This invention relates to improvements in musical instruments, such as saxophones, clarinets and similar instruments, the general object of the invention being to provide a key arrangement that will eliminate the awkward arrangement now in use and will facilitate the manipulation of the keys so that the finger action is greatly improved which will permit rapid execution of musical passages.

Another object of the invention is to provide means whereby the side keys for the high notes can be operated from certain of the other keys and by a master key. Another object of the invention is to provide auxiliary openings in the instrument which are paired with certain of the regular openings and to control these auxiliary openings by valves which are controlled from the master key and by certain of the regular keys so that the air passages are not impaired or obstructed and thus insure the production of "open" tones.

Another object of the invention is to provide means whereby the side keys or the keys for the high notes can be actuated independently of the keys to which they are connected.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an elevation of part of a saxophone which is constructed in accordance with this invention.

Figure 2 is a section on line 2-2 of Figure 1.

Figure 3 is a section on line 3-3 of Figure 1.

Figure 4 is a section on line 4-4 of Figure 1.

Figure 5 is a section on line 5-5 of Figure 1.

Figure 6 is a detail view showing how the master key will operate the octave key.

Figure 7 is a view of a modification.

Figure 8 is a section on line 8-8 of Figure 7.

Figure 9 is a sectional detail view showing one of the arm arrangements for holding the keys in open position.

Figure 10 is a section on line 10-10 of Figure 7.

Figure 11 is a perspective view of one of the keys shown in Figure 7 and used for independent operation of the high note valves.

Figure 12 is a detail view showing the connection between two of the sleeves shown in Figure 7.

Figure 13 is a detail view showing the connection between the arm on the master key shaft and the arm for the D key and

Figure 14 is a section taken on line 13-13 of Fig. 1.

Saxophones and similar instruments now in use have some of the keys arranged at the side of the instrument and the finger parts of these keys are so arranged that it is difficult to obtain rapid execution of musical passages by the manipulation of these keys. The valve openings in instruments as now constructed are also so arranged that false or artificial fingering must be resorted to to produce certain notes which impairs the air passages and renders it extremely difficult to secure proper execution of musical passages. In order to overcome these defects or disadvantages I eliminate the finger pieces on the stems of the side keys and provide means whereby these keys can be actuated from certain of the other keys, and I also provide auxiliary valve controlled openings which are paired with certain of the other openings. In the drawings a portion of the horn is shown at 1 and the valves for the side openings are shown at 2, 3, and 4. The stems 5 of these valves are pivoted on a shaft 6. Each stem is engaged by a spring 7 which tends to hold the valve in open position but said valves are normally held in closed position by means of an arm 8 having a cross piece 9 thereon which engages the three stems, the arm being arranged on a rock shaft 10 which is provided with a spring 11 which holds it in a position with the cross piece pressing upon the stems of the valves and forcing them upon their seats, this spring 11 being stronger than the springs 7. The lower end of the shaft 10 is provided with a finger piece 12 by which it can be rocked against the action of its spring 11. The valve 13 for the high E key has its stem 14 rotatably mounted on the shaft 10

65

70

85

90

95

100

105

110

and said shaft 10 has an arm 15 thereon which engages the valve 13 to hold it on its seat. A spring 16 engages the stem 14 and tends to hold the valve off its seat. Auxiliary outlets 17 are made in the horn and are arranged in a row at the side of the horn. Each outlet is paired with a certain regular outlet of the horn and these outlets are controlled by the valves 18, 19, 20 and 21. The stems of the valves 18 and 19 are connected to a sleeve 22 rotatably mounted on a shaft 23 supported on the horn and the valves 20 and 21 have their stems connected to a sleeve 24 which is also rotatably supported on a shaft 23. The abutting ends of these sleeves are each provided with an ear 25, these ears being engaged by a cross piece 26 on an arm 27 which is connected with the shaft 10. Each sleeve is connected with a spring 28 which tends to hold the sleeve in a position with the valves open but these springs are of less strength than the spring 11 connected with shaft 10 so that the valves are kept closed by the action of said spring 11 causing the cross piece 26 on the arm 27 to press against the ears on the sleeves and thus moving the sleeves to a position to close the valves. An arm 29 is connected with the stem of key 30 of the A valve and this arm extends under a small arm 31 on the sleeve 24 and as the spring of the A key or valve is stronger than the spring 28 of sleeve 24 the valves 20 and 21 will be held closed as long as the A valve 30' is in open position. An arm 32, actuated by the movement of the B key 33, extends under a small arm 34 on the sleeve 22 so that the valves 18 and 19 will be closed when the B valve or key is in raised position. When the B valve is in lowered position the spring 28 will raise the valves 18 and 19 provided the finger piece 12 of shaft 10 is being held depressed.

The rock shaft 35 of the G key 36 has an arm 37 thereon which will engage the stem of valve 3 so that this valve 3 will be moved in unison with the key 36. An arm 38 engages the stem 5 of valve 2 and is connected with the link 39 which is oscillated by the movement of the B key 33 so that the F valve 2 will be moved in unison with the B valve or key. An arm 40 engages valve 13 of the E key and is carried by the rock shaft 41 which is rocked by the movement of the A key 30 and its valve 30'. The rock shaft 10 has an extension 10' which engages a tilting member 42 which manipulates the ring 43 of the octave key.

From the foregoing it will be seen that with the fingers on keys 36, 30 and 33 being the G-A-B keys, pressing these keys down, and with a finger of the other hand pressing the finger piece 12 down the valves 18, 19, 20 and 21 will be opened and valves 2, 3, and 13 will be closed and D key 4 will be opened. When G key 36 is released valve

3 opens. When A key 30 is released E valve 13 is also released and valves 20 and 21 are closed. When B key 33 is released valves 18 and 19 are closed and F key 2 opens. When the finger piece 12 is depressed the octave key opens by the movement of ring 43 through the extension 10' of the rock shaft 10 and the member 42.

As will be seen the rock shaft 10 with its finger piece 12 and its arms constitutes a master key for holding the valves 18, 19, 20 and 21 closed as well as the valves 2, 3, 4 and 13 to permit independent movement of the G, A and B keys. It will also be seen that the valves 2, 3 and 13 are controlled from the G, A and B keys and these keys also control the auxiliary valves when the master key is depressed.

In the modification the high note valves 4', 3', 18' and 2' are arranged in a row with the stem of each valve fastened to a sleeve 44, the sleeves being rotatably mounted on a shaft 45 mounted on the horn and the first valve 41 is provided with a projection 46 which overlaps the second valve and this second valve is provided with a similar projection which overlaps the third valve and the third valve is provided with a similar projection which overlaps the 4th valve. The 4th valve is also provided with a projection 46. The projections are each engaged by an arm 47, the arms being each connected with a sleeve 48, the sleeves being rotatably mounted on a shaft 49 supported on the horn and the first three sleeves are each provided with a curved projection 50 for overlapping an inclined projection 51 on the next sleeve so that the sleeves of the valves 3', 18' and 2' cannot be moved until the sleeve of valve 4' is moved. This latter valve and its sleeve are held against movement by an arm 52 on the rock shaft 10' of the master key, which engages a hook 54 on the arm 47' for the valve 4'. A spring 55 is connected with each of the sleeves 44 in such a manner as to hold the valves 4', 3', 18' and 2' in closed position. A spring 56 is associated with each arm 47 and tends to press the arm upwardly against the projection 46 and these springs 56 are of greater strength than the springs 55 and thus the spring pressed arms will tend to hold the valves in open position against the action of the springs 55. This opening movement, however, is prevented by the spring of the master key pressing the arm 52 against the hook-shaped part 54 of the arm 47' so that as long as the master key is not operated the valves will remain in closed position due to the action of the springs 55. An arm 57 rests upon the arm 47 of valve 3' and this arm 57 is connected with the rock shaft 58 of the G key 36'. An arm 59 rests upon the arm 47 for the valve 18' and is connected with the rock shaft 60 of the A key 30'.

which controls the A valve 30'. An arm 61 rests upon the arm 47 of the valve 2' and is connected with the link 62 of the B key 33'. Thus the valves 4', 3', 13' and 2' are controlled by the master key and the G key, A key and B key as in the first form. In addition I provide a key lever 63 for opening each valve directly. Each key lever is provided with a key 64 at one end and an upwardly extending projection 65 at its other end, this projection engaging the under surface of a part of each valve. It will be seen, however, that when the lever for the valve 2' is operated the movement of this valve 2' will open the other valves due to the projections 46. In other words when the valve 2' is opened by its key the other three valves will also be opened. When the valve 3' is opened by its key, valves 3' and 4' will be opened but valve 2' will remain closed. When valve 3' is opened by its key, valve 4' will be also opened while valves 2' and 13' will remain closed. When valve 4' is opened by its key lever the other valves will remain closed. From the foregoing it will be seen that the same results will be secured in the modified form of the invention as those secured in the first form and in addition the high note valves at the upper end of the device can be manipulated by their own keys. In the second form of the invention the actions are reversed but the same results secured.

By my key arrangement easy finger action is secured which produces rapidity of execution of high tones; these tones can be executed by a simple and legitimate fingering without the use of false or artificial fingering. Said tones will be "open" tones as the air passages will not be impaired or broken by artificial fingering regardless of the fact that the G, A and B keys are used for the execution of these notes. These open tones are made possible by the use of the auxiliary outlets, the valves of which will work in conjunction with the regular valves but in reverse direction therefrom. When the G, A and B keys are being used for the production of regular notes or lower tones the auxiliary means will remain inactive as they will then be under the control of the master key.

What I claim is:—

1. In a musical instrument of the reed type and including high tone valves and lower tone valves, auxiliary valves associated with some of the lower tone valves, means for controlling some of the high tone valves from certain of the lower tone valves, means for controlling the auxiliary valves from certain of the lower tone valves and means for holding the high tone valves and the auxiliary valves inactive while the lower tone valves are to be used alone.

2. In a musical instrument of the reed

type and including high tone valves and lower tone valves, auxiliary valves associated with some of the lower tone valves, means for controlling some of the high tone valves from certain of the lower tone valves, 70 means for controlling the auxiliary valves from certain of the lower tone valves and a master key for holding the high tone valves and the auxiliary valves inactive while the lower tone valves are to be used alone, 75

3. In a musical instrument of the reed type and including high tone valves and lower tone valves, auxiliary valves associated with some of the lower tone valves, means for controlling some of the high tone 80 valves from certain of the lower tone valves, means for controlling the auxiliary valves from certain of the lower tone valves, a master key for holding the high tone valves and the auxiliary valves inactive while the 85 lower tone valves are to be used alone, and an individual key for each high tone valve.

4. In a musical instrument of the reed type and including high tone valves and lower tone valves, auxiliary valves associated with some of the lower tone valves, means for controlling some of the high tone valves from certain of the lower tone valves, means for controlling the auxiliary valves from certain of the lower tone valves, 90 a master key for holding the high tone valves and the auxiliary valves inactive while the lower tone valves are to be used alone and means whereby a high tone valve 95 will open when the master key is actuated. 100

5. In a musical instrument of the reed type and including high tone valves and lower tone valves, auxiliary valves associated with some of the lower tone valves, means for controlling some of the high tone 105 valves from certain of the lower tone valves, means for controlling the auxiliary valves from certain of the lower tone valves, a master key for holding the high tone valves and the auxiliary valves inactive 110 while the lower tone valves are to be used alone and means for actuating the octave key by the master key.

6. In a musical instrument of the reed type and including high tone valves and lower tone valves, auxiliary valves associated with some of the lower tone valves, means for controlling some of the high tone valves from certain of the lower tone valves, means for controlling the auxiliary valves from certain of the lower tone valves, 120 a master key for holding the high tone valves and the auxiliary valves inactive while the lower tone valves are to be used alone, means whereby a high tone valve will 125 open when the master key is actuated and means for actuating the octave key by the master key.

7. In a musical instrument of the reed type and including high tone valves and 130

- lower tone valves, auxiliary valves associated with some of the lower tone valves, means for controlling some of the high tone valves from certain of the lower tone valves, means for controlling the auxiliary valves from certain of the lower tone valves, a master key for holding the high tone valves and the auxiliary valves inactive while the lower tone valves are to be used alone, means whereby a high tone valve will open when the master key is actuated, means for actuating the octave key by the master key, and an individual key for each high tone key.
15. In a musical instrument of the reed type and including high tone valves and lower tone valves, auxiliary valves associated with some of the lower tone valves, means for controlling some of the high tone valves from certain of the lower tone valves, means for controlling the auxiliary valves from certain of the lower tone valves, a master key for holding the high tone valves and the auxiliary valves inactive while the
- 20
- 25
- 20
- 25

lower tone valves are to be used alone, a key for actuating each high tone valve, a projection on each high tone valve which extends over the next valve above so that the opening movement of the upper valves will be communicated to the lower valves of the high tone group.

9. In a musical instrument of the reed type and including high tone valves and lower tone valves, auxiliary valves associated with some of the lower tone valves, the auxiliary valves being connected together in pairs so that the valves of each pair will move in unison, means for controlling some of the high tone valves from certain of the lower tone valves, means for controlling the pairs of auxiliary valves from certain of the lower tone valves and a master key for holding the high tone valves and the auxiliary inactive while the lower tone valves are to be used alone. 45

In testimony whereof I affix my signature.

AVERY J. HILTON.
